RAILWAY-TRAFFIC-CONTROLLING APPARATUS

Application filed December 8, 1927. Serial No. 238,548.

My invention relates to railway traffic controlling apparatus, and particularly to automatic train controlling apparatus of the intermittent inductive type.

5 I will describe two forms of apparatus embodying my invention, and will then point out the novel features thereof in claims.

In the accompanying drawing, Fig. 1 is a 10 diagrammatic view showing one form of apparatus embodying my invention. Fig. 2 is a diagrammatic view showing a modified form of the apparatus illustrated in Fig. 1 and also embodying my invention.

Similar reference characters refer to similar parts in both views.

Referring first to Fig. 1, the reference character A designates a train carried receiver comprising a magnetizable core B and a magnetizable bridging member C. In the form 20 illustrated in the drawing the left-hand end of the core B is provided with a leg 3 extending toward the left-hand end of the bridging member C but spaced therefrom by an air gap 4. Core B terminates in a pole 25 2 adjacent the trackway. The core B is also provided with a leg 5 adjacent the left-hand end of member C but spaced therefrom by an air gap 6. Furthermore, a leg 7 on core B extends toward the right-hand end of the 30 member C but is spaced from the member by an air gap 12. The right-hand end of the member C terminates in a pole 8 similar to pole 2 of core B.

Located on core B between legs 3 and 5 is 35 a primary 1 which is constantly supplied with alternating current from a generator G, the circuit for this winding preferably but not necessarily including a condenser 27 by means of which the circuit is tuned to resonance at 40 the frequency of the current supplied by the generator G. The member C carries a secondary 9 which is provided with a circuit including the winding of a relay R and a front contact 11 of this relay. The circuit for secondary 45 9 is also preferably, but not necessarily, tuned to resonance, at the frequency of the current supplied by generator G, by means of a condenser 10. The relay R may be utilized in many suitable manner to control train 50 carried governing means; as here shown a

front contact 13 of this relay is included in circuit with a battery 14 and a lamp 15 so that the lamp will be lighted when the relay is energized. It will be observed that the flux created in core B by the current in primary 1 55 takes two paths, a portion of this flux traversing the path including leg 3, air gap 4, member C, air gap 6 and leg 5, and another portion of the flux traversing a magnetic circuit including the left-hand end of core B, pole 2, the air gap between poles 2 and 8, member 60 C, air gap 12 and leg 7. The parts are so proportioned that the reluctances of those portions of the core B and the member C which are included in the circuits just described form a comparatively insignificant part of the total reluctances of these circuits. It will be plain, therefore, that the magnetic structure of the receiver A is analogous to the electric circuits well known to the art in 65 the form of a Wheatstone bridge, the air gaps 4 and 6 forming two arms of the bridge and the air gap between poles 2 and 8 and the air gap 12 forming the other arms of the bridge. 70

Located in the trackway is a controlling 75 element D comprising a magnetizable core 16 provided with a winding 17. The winding 17 is provided with a circuit including a reactor 19 and a condenser 18 and controlled by the front contact 20 of a relay J. The relay 80 J may in turn be controlled in any suitable manner and when this relay is energized the circuit is closed for winding 17 of element D, the parts being so proportioned that the reactances of 18 and 19 are substantially equal 85 and opposite at the frequency of the current supplied by generator G. The element D is located adjacent the path of travel of the receiver A and is so disposed that when the receiver passes over the element D, the core 90 16 is introduced in the air gap between the poles 2 and 8 of the receivers. The parts are so proportioned that if the circuit for winding 17 is open when the receiver A is over the element D, the ratio of the reluctances of air 95 gaps 4 and 6 is equal to the ratio of the reluctance of the path between poles 2 and 8 through the core 16 to the reluctance of air gap 12. This is the condition for balance of the magnetic bridge, that is to say, under 100

these conditions the magnetic potentials of the two ends of the core C are equal so that there is substantially no flux linking the secondary 9. Under these conditions, therefore, no electromotive force is induced in secondary 9 and relay R is de-energized. When the receiver is not located over the element D, the reluctance of the path between poles 2 and 8 is considerably greater than when the core 16 is included in this path and under these conditions the bridge is unbalanced so that the magnetic potentials at the two ends of the bridge member C are unequal and an alternating flux links secondary 9 to induce in this winding an electromotive force which is effective to supply to relay R a sufficient current to hold the relay in its energized condition. The path of the predominating or effective flux through secondary 9 under these conditions may be traced from primary 1 on core B, through leg 3, air gap 4, member C, air gap 12, leg 7, and core B back to primary 1.

It is of course well known that eddy currents in the iron portions of the receiver A and the trackway element D will cause magnetomotive forces which are substantially 90° out of phase with the magnetomotive force created by primary 1. The receiver and the trackway element should therefore be so proportioned that these quadrature magnetomotive forces in the separate arms of the magnetic bridge are in the same ratio as the reluctances of the air gaps so that there will be no electromotive force induced in secondary 9 when the receiver is over an element D having its winding 17 open circuited.

In explaining the operation of the apparatus, I will first assume that when the train passes over the trackway element D, the contact 11 of relay J is open, so that the circuit for winding 17 is open. Under these conditions the introduction of the core 16 with the magnetic path between poles 2 and 8, decreases the reluctance of this path to the value at which the bridge is balanced so that no flux links secondary 9 and relay R becomes de-energized to display a stop indication on the train. Inasmuch as the circuit for relay R includes a front contact 11 of this relay, the relay when once open, will remain open until the path through the front contact 11 is shunted. This shunting may be accomplished, for example, by a push button 21 connected in multiple with contact 11.

If contact 20 of relay J is closed when the train passes over the element D, the effect of this element on the train carried apparatus is neutralized to such an extent that the relay R remains closed, that is to say, when the circuit for winding 17 is closed, this winding practically nullifies the effect of the core 16 on the receiver A.

In actual practice, it is customary to locate the relay J at a considerable distance from

the element D. Under these conditions, I prefer to locate the reactor 19 adjacent the relay J, and to locate the condenser 18 adjacent the core 16. Under these conditions if a short occurs between the wires extending from the element D to the relay J, that is, if these wires become connected together, the circuit then closed for winding 17 will have a comparatively high impedance, and if a train passes the element D, relay R will become de-energized.

I prefer to construct the reactor 19 with an air core since its power factor, and hence the tuning of the circuit for winding 17 will be independent of the power supplied to the element D from the receiver A. The tuning of the circuit for winding 17 will then be independent of the spacing between the receiver and the core 16 and will also be independent of the fluctuations in the electromotive force of generator G. The reactor 19 should have a low power factor so that the total impedance of the circuit for winding 17 will be low, and for the further reason that the condenser 18 will then have the greatest impedance for a given resistance of reactor 19 when the lead wires are shorted. An air core reactor having these characteristics is easier to obtain than one having an iron core, particularly for use with higher frequencies of the order of those mentioned hereinafter.

It is obvious that train carried receivers of the type here shown will pass over masses of iron located in the trackway, such as the rails of cross-overs, etc. It is undesirable for such masses of iron to produce a stop indication on board the train and I therefore prefer to so construct the apparatus that it will distinguish between control elements D located in the trackway and any other masses of iron which may be located adjacent the path of travel of receiver A. It is, of course, well known that the permeability of iron is a function of the intensity of the magnetic field. The permeability of air, however, is independent of the field strength and I therefore propose to supply a comparatively small current to the primary 1 so that the magnetic field will be comparatively weak. Under these conditions, the permeability of the iron cores B and 16 and of the member C will be near the value of the initial permeability for the material and the reluctance of the core 16 will comprise a considerable part of the total reluctance of the magnetic path between poles 2 and 8 and including this core.

In one embodiment of my invention, I have discovered that with a magnetomotive force of approximately 10 ampere turns supplied by primary 1, it is possible to construct the receiver A and the element D in such manner that the reluctance of the core 16 amounts to approximately 10% of the total reluctance of the magnetic circuit including core B,

10 pole 2, core 16, pole 8, member C, air gap 12, and leg 7. Furthermore, I construct the cores B and 16 and the member C of material having a considerably higher initial permeability than that of iron or steel of the formula usually used for railway rails and similar members. It follows, therefore, that for the low values of the magnetic field supplied by the primary 1 the reluctance of a track rail or other stray mass of iron in the trackway 15 will be so great that the change caused by passing such track rail or mass of iron will not vary the ratio of the reluctance of the arms in the magnetic bridge by a sufficient amount to de-energize relay R.

15 With the apparatus constructed in this fashion therefore, the train carried apparatus will respond to the trackway element D having its winding open-circuited, to de-energize relay R, but relay R will not become de-energized when the receiver passes any other mass of iron in the trackway.

20 Referring now to Fig. 2, the receiver A¹ has a physical arrangement somewhat different from the receiver A of Fig. 1 but operates in the same manner. In Fig. 2 the flux from primary 1 traverses two paths, a portion traversing the path through core B¹, air gap 4, bridge C¹ and air gap 6, and another portion of the flux traversing the path from core B¹, through pole 2, the air gap between poles 2 and 8, and thence through member C¹ and air gap 12 to core B¹. It will be plain, therefore, that the magnetic 25 structure of receiver A¹ comprises a bridge similar to the structure already described in connection with Fig. 1. The parts are so proportioned that under normal conditions, the bridge is unbalanced so that an alternating flux links secondary 9 and an alternating electromotive force is induced in this secondary. The secondary 9 is provided with a circuit including the primary of a transformer T and a tuning condenser 10. The 30 secondary of transformer T is connected with the primary of a transformer K, through an amplifier 23 of any suitable form. The secondary of transformer K is connected through a rectifier 22, with a winding of relay R over a front contact 11 of this relay. Relay R controls a lamp 15 in the same manner as in Fig. 1. The electromotive force induced in secondary 9 is therefore effective to hold relay R closed under normal 35 conditions. When the receiver A¹ passes an element D having its winding 17 open circuited, the consequent reduction in the reluctance of the air between poles 2 and 8 balances the magnetic bridge so that the ratio of the reluctance of air gap 4 to the reluctance of air gap 6 is equal to the ratio of the reluctance of the path between poles 2 and 8 to the reluctance of air gap 12. Under these conditions no electromotive 40 force is induced in secondary 9 and relay R

becomes energized. When front contact 20 of relay J is closed to complete the circuit for winding 8 the element D has practically no effect upon the train carried receiver. The magnetizable portions of the receiver A¹ and the element D are constructed of material having a high initial permeability, and the magnetomotive force supplied by the primary 1 is of a low order of magnitude to permit the receiver to distinguish between the element D and stray masses of iron in the trackway in a manner already described in connection with Fig. 1. In order to assist in this distinction the cores B and 16 and member C may be laminated, and the current supplied by generator G may be of a comparatively high frequency, such for example as, 1000 cycles per second. With frequencies of this order, there is a marked "skin" effect observed in stray masses of iron which are introduced into the field of receiver A¹. Due to this "skin" effect, there is comparatively small penetration of the alternating flux and as a result the effective reluctances of such stray masses of iron are 50 comparatively high and these masses of iron can not cause sufficient variation in the reluctance of the path between poles 2 and 8 to balance the bridge and cause de-energization of relay R. Due to the laminated construction of the core 16 of element D, however, the increased area of iron thus introduced into the magnetic field of the receiver A, decreases the effective reluctance of the core 16 and the consequent change in the 55 total reluctance of the magnetic path between poles 2 and 8 is sufficient to de-energize relay R.

60 It should be observed that tractive armature relays of the usual form can not be operated satisfactorily on currents having frequencies of the order of 1000 cycles per second. It is for this reason that I have introduced the rectifier 22 in the circuit for relay R. With the rectifier inserted in the 65 relay circuit, currents of any frequency may be utilized in the receiver windings, the relay operating perfectly on the rectified current.

70 It should be pointed out that if desirable, an amplifier and rectifier may be inserted between the relay R and secondary 9 in Fig. 1 in the same manner as has already been described in connection with Fig. 2.

75 Although I have herein shown and described only two forms of railway traffic controlling apparatus embodying my invention, it is understood that various changes and modifications may be made therein within the scope of the appended claims without departing from the spirit and scope of my invention.

80 Having thus described my invention, what I claim is:

85 1. Railway traffic controlling apparatus

comprising a train carried receiver having a source of magnetomotive force, two magnetic circuits each supplied with flux from said source, a magnetizable member connecting a first point in one such circuit with a second point in the other circuit which is normally at a different magnetic potential from said first point, governing means on the train controlled by the flux in said member, and means located in the trackway for at times varying the reluctance of a portion of one of said magnetic circuits to make equal the magnetic potentials of said first and second points.

2. Railway traffic controlling apparatus comprising a train carried receiver having a source of magnetomotive force, a first magnetic circuit including said source and a first and second air gaps, a second magnetic circuit including said source and a third and fourth air gaps, a magnetizable member connecting a point in said first circuit between the first and second air gaps with a point in the second circuit between the third and fourth air gaps, governing means responsive to the flux through said member, and means located in the trackway for at times changing the reluctance of one of said air gaps to such a value that the ratio of the reluctances of the first and second air gaps is substantially equal to the ratio of the reluctances of the third and fourth air gaps.

3. Railway traffic controlling apparatus comprising a train carried receiver having a source of magnetomotive force, a magnetic bridge having a first and a second arms supplied with flux from said source, a third and a fourth arms supplied with flux from said source, a magnetizable member connecting the common point of said first and second arms with the common point of the third and fourth arms, means located in the trackway for at times varying the ratio of the reluctances of the third and fourth arms, and governing means responsive to the flux in said member.

4. Railway traffic controlling apparatus comprising a train carried receiver having a source of magnetomotive force, a magnetic bridge having a first and a second arms supplied with flux from said source, a third and a fourth arms supplied with flux from said source, a magnetizable member connecting the common point of said first and second arms with the common point of the third and fourth arms, means located in the trackway for co-operating with said receiver at times to vary the reluctance of one of said arms so that the ratio of the reluctances of the first and second arms equals the ratio of the third and fourth arms, and governing means responsive to the flux in said member.

5. Railway traffic controlling apparatus comprising a train carried receiver having a source of magnetomotive force, a magnetic

bridge having a first and a second arms supplied with flux from said source, a third and a fourth arms supplied with flux from said source, a magnetizable member connecting the common point of said first and second arms with the common point of the third and fourth arms, means located in the trackway for co-operating with said receiver at times to vary the reluctance of one of said arms so that the ratio of the reluctance of the first and second arms equals the ratio of the third and fourth arms, a winding on said bridging member, and governing means controlled by said winding.

6. Railway traffic controlling apparatus comprising a train carried receiver having a magnetizable core, a source of magnetomotive force on said core, a magnetizable bridging member having one end spaced from said core by two air gaps and having the other end spaced from the core by two other air gaps, a winding on said bridging member, governing means controlled by said winding, means located in the trackway to at times vary the reluctance of one only of said air gaps to a value for which no electromotive force is induced in said winding, and governing means controlled by said winding.

7. Railway traffic controlling apparatus comprising a train carried receiver having a source of magnetomotive force, a magnetic bridge having a first and a second arms supplied with flux from said source, a third and a fourth arms supplied with flux from said source, a magnetizable member connecting the common point of said first and second arms with the common point of the third and fourth arms, means located in the trackway for co-operating with said receiver at times to vary the reluctance of one of said arms so that the ratio of the reluctance of the first and second arms equals the ratio of the third and fourth arms, a winding on said member, a relay receiving energy from said winding, a rectifier interposed between said relay and said winding, and governing means controlled by said relay.

8. In combination, a train carried receiver comprising a magnetizable member, a source of magnetomotive force of the order of ten ampere turns associated with said member, a winding on the member, an amplifier having its input terminals receiving energy from said winding, governing means on the train receiving energy from the output terminals of said amplifier, and a magnetizable core of high initial permeability located in the trackway adjacent the path of travel of said receiver and co-operating therewith to at times vary the flux through said winding.

9. In combination, a train carried receiver comprising a magnetizable member having a primary and a secondary, means for supplying the primary with alternating current at a frequency of the order of one thousand
